UNITED STATES PATENT OFFICE

SAM B. HUTTON, OF TRENTON, NEW JERSEY, ASSIGNOR TO EASTERN CABINET COMPANY, OF TRENTON, NEW JERSEY

CABINET AND EXTENSIBLE TOP THEREFOR

Application filed January 26, 1932. Serial No. 588,998.

This invention relates broadly to furniture, having particular reference to a cabinet and more particularly to an extensible top for the cabinet whereby the latter may also be used conveniently as a table.

Further, in accordance with the present invention an extensible top is provided for use with cabinets, tables, and similar articles of furniture.

10 The invention together with its numerous objects and advantages will be best understood from the following description, taken in connection with the accompanying drawings wherein:

15 Figure 1 is a front elevational view of a cabinet and top therefor embodying the features of the present invention.

Figure 2 is a side elevational view thereof two positions of the table top being suggested.

20 Figure 3 is a vertical sectional view taken substantially on the line 3—3 of Figure 2.

Figure 4 is a top plan view of the cabinet with the top removed.

25 Figure 5 is a vertical sectional view taken substantially on the line 5—5 of Figure 1.

Figure 6 is a view similar to Figure 5, except that the table top is shown extended.

Figure 7 is a detail sectional view taken substantially on the line 7—7 of Figure 1.

Figure 8 is a fragmentary bottom plan view of one leaf of the table top.

Figure 9 is a detail sectional view taken substantially on the line 9—9 of Figure 5.

30 Figure 10 is a perspective view of a guide cleat.

With reference more in detail to the drawings, it will be seen that 10 designates generally a cabinet, the same being substantially of conventional construction and being provided with suitable drawers and compartments as suggested, and is preferably of the shape and construction shown generally in the drawings.

35 In carrying out the present invention the cabinet 10 is characterized by a top frame 11 the front and side members of which are connected by relatively spaced transverse bars 12 to the outer sides of which are secured longitudinally extending guide rails 13.

My improved top, designated generally by the reference character 14 comprises two substantially identically shaped sections or leaves 15, 16 and each of these leaves has an edge configuration conforming substantially 55 to the configuration of the cabinet 10 in cross section, and each leaf is also of suitable dimension so that either may serve singly as a top for the cabinet.

In the present instance one of the leaves, 60 for example the leaf 15 is provided on the under side thereof with a pair of opposed angle rail engaging cleats 17 secured to said leaf or section 15 through the medium of countersunk screws or other fastening elements 18.

The leaves or sections 15, 16, at corresponding edges thereof are hingedly connected together as at 19, and it will be seen that through the medium of the cleats 17 engaging 70 the rails 13 the leaf 15 is constrained to slide transversely of the cabinet 10, and is secured against displacement longitudinally relative to the cabinet and also in a plane perpendicular to the cabinet.

75 From a study of Figure 4 it will be noted that the rail engaging cleats 17 are secured to the table top section 15 adjacent the hinged edge thereof, and that these cleats 17 are slightly less in length than one half the length 80 of the rails 13 whereby the table top section 15 is free to slide transversely of the cabinet. Normally, the table top section 15 is arranged on the frame 11 so as to serve of itself, as a top for the cabinet. When so 85 serving this function, the table top section 15 is in the position suggested in Figure 5, and the table top section 16 depends downwardly therefrom adjacent to and in parallelism with the rear wall of the cabinet as is 90 also shown in Figure 5.

To increase the size of the top of the cabinet the section 15 is slid forwardly from the left to the right in Figure 5 whereupon section 16 slides over the upper edge of the rear 95 member of the frame 11 to rest on the frame coplanar with the section 15 as shown in Figure 6.

The table top section 15 adjacent its transverse center line has anchored thereto as at 100

20 a spring latch 21 provided adjacent its free end with an abutment shoulder 22 and continuing forwardly from the shoulder to provide a cam end 23. For accommodating 5 the shouldered end portion of the latch 21, the table section 15 on its under side is provided with a slot or recess 24 elongated longitudinally and having its top wall inclined as shown in Figure 7. Adjacent the deepest 10 end of the slot 24 and slightly spaced forwardly thereof the table top section 15 is provided with a second notch or recess 25 for accommodating the terminal of the spring latch 21.

15 Adjacent its transverse center line the front member of frame 11 is slightly notched as at 26, and thus it will be seen that as the table section or leaf 15 is pulled forwardly, the cam surface 23 rides over the bottom surface 20 of the notch 26 forcing the shoulder portion of the latch 21 up into the recess 24 and the terminal of the catch up into the recess 25. When the table section 15 has been pulled forward a sufficient distance so that the cam portion 23 of the latch has passed entirely 25 through the notch 26 the latch member 21 because of its inherent resiliency will spring downwardly so that the shoulder 22 will engage the front side of the frame 11 as shown 30 in Figure 7.

When the shoulder 22 is thus engaged with the front side of the frame 11 the forward end of the angle cleats 17 will be in engagement with the rear side of the front member 35 of frame 11 as suggested in Figure 6 whereupon the table top 14 in its extended position will be securely held against displacement relative to the frame 11 in any and all directions.

40 When it is desired to decrease the size of the table top that is to move the sections back to the position shown in Figure 5 with the section 16 paralleling the rear wall of the cabinet 10, it is necessary only to first force the 45 shoulder end 22 and also cam terminal 23 of the shank 21 upwardly into the recesses 24, 25 and the section 15 may then be slid rearwardly or from the right to the left in Figure 6 to assume the position shown in Figure 5.

50 Even though I have herein shown and described the preferred embodiment of the invention it is to be understood that the same has been herein illustrated and described somewhat in detail only for the purpose of 55 illustrating a practical embodiment of the invention, and accordingly it is to be understood that I claim all such forms of the invention to which I am entitled, in view of the requirements of the prior art and the scope of 60 the appended claims.

Having thus described my invention, what I claim as new is:

65 1. In combination, a frame including a pair of relatively spaced transverse rails, a table top comprising a pair of hingedly con-

nected sections, L-shaped cleats secured to the under side of one of the table top sections and engaging said rails, said cleats being in length substantially half the length of said rails and having abutting engagement with portions of the frame for restricting transverse movement of said one table top section relative to said frame, a spring latch member secured to the under side of said one table top section and adapted to engage said frame when the said table top section is at its limit of movement in one direction relative to said frame; and said one table top section being also provided on its under side with a pocket for receiving a portion of said latch, the relative arrangement of said pocket and latch being such as to permit movement of the latch to a position as not to interfere with the desired shifting of said one table top section.

2. In combination a supporting frame, a table top supported thereby, interengaging means on the frame and on the table top for securing the table top on the frame for sliding movement relative thereto, a latch member formed of spring metal anchored at one end to the under face of said table top and provided adjacent its free end with a frame engaging shoulder, and a cam portion in advance of said shoulder, said table top on its under side being also provided with a pocket for accommodating the shoulder equipped end of said latch and in advance of said pocket with a recess for substantially receiving said cam; said cam being engageable with the frame upon movement of the table top in one direction relative to the frame for causing said shoulder equipped portion of the latch into the first named pocket until said cam has passed beyond the frame.

In testimony whereof I affix my signature.

SAM B. HUTTON.
